TELEVISION VIEWING SCREEN

Otto H. Schade, West Caldwell, N. J., assignor
to Radio Corporation of America, a corporation
of Delaware

Original application October 17, 1940, Serial No.
361,503, now Patent No. 2,302,147, dated No-
vember 17, 1942. Divided and this application
March 24, 1942, Serial No. 435,923

6 Claims. (Cl. 178—5.4)

My invention relates to the reception of television images in natural color and particularly to reflection and luminescent-type screens for such reception, and is a division of my copending application, now issued as Patent 2,302,147, November 17, 1942.

It has been proposed to transmit television images in color by successively exposing a photo-sensitive target electrode through successively displaced primary color filters to the illuminated object of which an image is to be transmitted. Use is made at the transmitter of a rotating filter containing two or more color filters, and a similar rotating filter at the receiving location is provided, such as in the path of the light between a cathode ray tube or light valve and the observer to recreate the television image in natural colors. The use of such a rotating shutter at the receiving location is objectionable in some cases because of the space required, inasmuch as it must be approximately twice the diameter of the cathode ray tube or light valve screen. A further disadvantage resides in the fact that considerable light is lost by such a filter system so that the light which may be created or controlled by the cathode ray or projection tube is not effectively utilized.

It is an object of my invention to provide a viewing screen for color picture presentation wherein all of the light of the various colors comprising the picture is effectively utilized; and it is a further object to provide a screen and system for recreating colored images which will occupy considerably less space than prior screens and systems. It is a still further object to provide a screen and image recreating system wherein substantially all of the light incident on the screen is converted to useful light representative of the recreated image. These and other objects, features and advantages of my invention will become apparent when taken in connection with the following description and accompanying drawing wherein:

Figure 1 shows an image projection system and screen made in accordance with my invention;

Figure 2 is a perspective view of the type of screen shown in Figure 1; and

Figure 3 is an end view of the screen shown in Figure 2 showing the method of rotating the various elements of the screen.

In accordance with one teaching of my invention, I provide a reflection-type viewing screen comprising a suitable number of opaque segmented sections preferably of twisted triangular prismatic form, successive faces of which are

made selectively reflective to light of various colors, such as red, blue and green, and I rotate these prismatic segments in a sequence determined by the recreation of the television image. 5 Further in accordance with my invention I provide a system wherein the recreated image consists of various intensities of ultra violet light, this light being projected upon a screen having one or more segments which are preferably of twisted triangular prismatic form, the surfaces being responsive to convert the ultra violet light into the primary colors, such as red, blue and green. In each of these preferred modifications of my invention the liberation of light of successive colors is controlled by the viewing screen itself and is not dependent upon the colored filters interposed between the light source and the viewing screen.

A colored image to be televised is broken up 10 at the transmitting station into a series of image fields of representative colors. A single frame of the television image may comprise three successive fields of red, blue and green successively scanned to generate a succession of image impulses representative of the optical image to be transmitted. The television image may be received by a conventional television receiver 1, shown schematically in Figure 1, having a cathode 20 ray tube 2 capable of recreating the television image which appears due to persistency of vision as a black and white replica of the original image such as upon a fluorescent screen 3 associated with the tube 2. The luminescent material comprising the screen 3 may be of mixed sulphides, the principal requirement being that each of the primary colors is present in the light generated by the screen. Preferably the luminescent materials used for the screen 3 should have a rapid 25 phosphorescent decay time, a property which is inherent in certain well known mixed sulphide screens. In accordance with known systems the image replica, which when viewed directly appears black and white on the screen 3, may be viewed in its natural colors by rotating a filter disc containing successively displaced filters transparent to the primary colors and viewing the screen through this disc which is operated in synchronism with a corresponding filter disc or 30 mechanism at the transmitter. However, in accordance with my invention and as shown by Figure 1, the light forming the black and white replica appearing on the fluorescent screen 3 is projected and focused such as by a lens system 35 4, which may be of the transmission or reflection

type, upon a viewing screen 5 on which the televised image appears in its natural colors.

Referring to Figure 2 which shows a perspective view of the screen 5, the screen comprises one or more individual light developing or reflecting members 30 having an equilateral triangular cross-section and the members are rotated in accordance with the recreation of the television image appearing on the screen 3. More particularly and with further reference to Figure 2, the members 30 are of prismatic form and are mounted with their axes normal to the horizontal direction of scanning represented by the dashed line 31 and are thus parallel with the vertical direction or frame scanning, that is, the lower rate of scanning, as indicated by the dashed line 32. In accordance with this teaching of my invention, the prismatic members 30 are helically twisted by an angle of approximately 120° from one end of the members 30 to the opposite end. The cross-section of each of the members 30 in a plane normal to the axis of the members is preferably triangular and the helically twisted surfaces may be said to be generated by moving the lines bounding the cross-section along the axis while revolving the bounding lines about the axis. The surfaces will have a progressively uniform form surface, provided the movement of the generating lines about the axis is proportional to the displacement along the axis, although this displacement may be made non-linear, provided the vertical deflection of the scanning spot of light is non-linear with time to a corresponding degree.

The members 30 are supported with their axes parallel and coplanar to one another and free to rotate, such as in a clock-wise direction as shown. I have shown in Figure 3 means for rotating the members 30 continuously comprising a gear wheel on each of members 30 with an intervening gear to provide rotation in the same direction. As the members 30 rotate in accordance with the frame rate of scanning, a section of line width will move progressively from the top of the members to the bottom, which is the direction of vertical scanning. The members are shown in Figure 2 in an instantaneous position at which an elemental line may be drawn along one of the surfaces of the members, the said line being continuous over the entire width of the screen comprising the members 30. The screen members are so synchronized with the frame rate of scanning that the light beam is incident on the members along this line as it progresses from the top to the bottom of the members during rotation thereof. Thus as shown in Figure 2, the screen may be scanned along the line 31 which is progressively and during successive scannings displaced in the direction of vertical scanning corresponding to the direction of the line 32. In accordance with my invention, each of the faces of the prismatic members 30 such as the faces 33, 34 and 35 are made to liberate light of one of the primary colors such as red, blue or green. Thus the faces may be made reflective to individual primary colors or these faces may be provided with coatings of different luminescent materials which successively luminesce with the three primary colors under excitation such as ultra violet light. Thus whether the faces are reflective to visible light or subjected to ultra violet light, light corresponding to the three primary colors is liberated. Since the members 30 are helically twisted by an angle of 120° from one end thereof to the other and are rotated in syn-

chronism with the frame rate of scanning, the light beam impinges on the members at a time when a surface of elemental line width is in the proper position for reflecting light to the observer. Since the curvature from top to bottom of the members is continuous, a scanning beam of light having very small cross-section is preferable.

As the scanning beam approaches the lower ends of the members 30 and, following scansion, is returned to the top of the members, the angular displacement of the surface along the length of the members places a surface capable of liberating a different color in position for scanning. Since the light beam return time or "fly back" time is finite, somewhat less than the full-length of the members is scanned in the vertical direction. However, a helical displacement of somewhat less than 120° may be provided, depending upon the time required for the return or fly back time, whereupon the full-length of the members may be scanned.

I have described the members 30 as being of triangular cross-section so that they may be aligned with a minimum of spacing between adjacent members. However, a single multi-face member may be used as the viewing screen and, in this case, the member may have more than three surfaces. Thus a member having an equilateral polygonal cross-section with more than three faces but preferably an integral multiple of three faces may be used, each face liberating a different primary color such as in regular sequence of red, blue and green. Obviously, such a single screen member may have surfaces liberating a number of colors greater than three, such as for a four or five color system of television transmission. The dimensions of each face of a single member screen correspond to full image size and the member is rotated at constant speed.

As indicated above the members 30, instead of having three reflective surfaces, reflective to different colors of light, may have the three surfaces coated with luminescent materials, each of which has a different spectral response characteristic when subjected to ultra violet radiation. When utilizing a viewing screen of this type, the fluorescent screen of the television receiving tube or the light source for a light valve is constructed to produce ultra violet light. Thus the fluorescent screen 3 may consist of pure zinc silicate having no fluorescent activator which, when scanned by an electron beam in a manner well known in the art, recreates an ultra violet television image wherein the light and shade areas of the original optical image are recreated in various intensities of ultra violet light. In accordance with this teaching of my invention, the ultra violet light from a sequentially scanned cathode ray tube or light valve is projected upon the segmented sections of prismatic form, the faces of which are responsive to the ultra violet light to generate various colors such as red, blue and green. One face of each of the triangular prismatic members 30 is provided with a coating 41 of material which, when subjected to ultra violet light, produces red light, whereas the coating 42 on one adjacent face produces blue, and the coating 43 on the other adjacent face produces green light under the influence of the ultra violet light from the fluorescent screen 3. For example, a luminescent material comprising 10 to 30% of zinc sulphide mixed with 70 to 90% cadmium sulphide may be used to form the luminescent material coating 41 capable of giving red light. Silver activated zinc sulphide may be used

for the luminescent blue responsive coating 42, and 30 to 40% zinc cadmium sulphide with 60 to 70% zinc sulphide may be used for the green responsive coating 43.

In operation the television image is received and converted into a light and shade replica wherein each of three successive fields of scanning is representative of a different primary color of the original optical image. Depending on the transmission standards chosen, the image may be transmitted at twenty frames per second, each frame consisting of three color fields successively red, blue and green or a vertical scanning field frequency of 60 cycles per second. The horizontal line definition is independent of the field frequency and may be chosen in accordance with the available frequency band width for transmission. With a vertical field frequency of 20 per second the members 30 having three faces should be rotated at a rate of 1200 revolutions per minute, whereas for 40 frames and 120 fields per second the rate should be 2400 revolutions per minute.

In my above-mentioned original application I disclosed other types of screens whereby my objects may be obtained and while in this application I have indicated only several preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

I claim:

1. A viewing screen scanned by a beam of light for television reception comprising an equilateral prism having similar warped lateral surfaces each being of a material which liberates light of a different color from the others when scanned by said beam.

2. A viewing screen scanned by a beam of light for television reception comprising a plurality of elongated prisms arranged side by side with their axes lying parallel to one another, each of said prisms having three similar warped lateral surfaces, each of the surfaces of each of said prisms being of a material which liberates light of a different primary color from the others when scanned by said beam.

3. In combination with means for developing a beam of light displaced in two mutually perpendicular directions at different rates over an image area, a viewing screen to intercept said beam of light and form an optical image observable by persistence of vision said screen comprising a prism with a plurality of similar warped surfaces surrounding an axis, each of said surfaces being of material capable of liberating diffused light of a different primary color from ad-

jacent surfaces, means to support said prism with its axis parallel to the direction of the lower rate of displacement of said beam of light so that during rotation thereof only an elongated elemental area extending in the direction of the higher rate of scanning is exposed in a normal image receiving position to said first-mentioned means at any instant of time, said area progressing axially with rotation of said member and means to rotate said member about its axis through the angle subtended by one of said surfaces during the displacement of said beam of light over said image area at said lower rate.

4. Apparatus as claimed in claim 3 wherein said first-mentioned means develops a beam of ultra-violet light and each of said surfaces is coated with luminescent material, the composition of the said material on one surface differing from that on adjacent surfaces whereby light of a different color is developed on each adjacent surface when subjected to said beam of ultra-violet light.

5. In combination with means for developing a beam of light scanned over an image area in two mutually perpendicular directions at different rates, a viewing screen to intercept said beam of light and form an optical image observable by persistence of vision, said screen comprising a plurality of rotatable prisms each having three similar warped surfaces surrounding an axis, each of the surfaces of each prism being of a material capable of liberating diffused light of a different primary color from that of adjacent surfaces, means to support said prisms with their axes in substantially a single plane parallel to the direction of the lower rate of scanning by said beam and means to rotate said members at a uniform rate about their respective axes through an angle of one hundred twenty degrees during the displacement of said beam of light over said image area at the lower rate of scanning.

6. In combination with means for developing an ultra-violet light beam scanned over an image area in successive series of mutually displaced parallel paths, a viewing screen including a plurality of rotatable prisms each having three similar warped surfaces surrounding an axis, each surface of each of said prisms being coated with luminescent materials of a composition differing from that of the coating on adjacent surfaces said luminescent materials being chosen to liberate visible light of a different color from each surface of each prism when scanned by said ultra-violet light beam, means to support said prisms with their axes parallel to one of said directions of scanning and means to rotate said members at a uniform rate about their respective longitudinal axes through an angle of one hundred twenty degrees during the displacement of said beam of light over said image area in said one of said directions.

OTTO H. SCHADE.
